DRIVE FOR WEB WINDING APPARATUS

Andrew Jack Seyerlein, Hasbrouck Heights, N. J.

Application March 11, 1952, Serial No. 275,885

3 Claims. (Cl. 242—55)

1

My invention relates to drives and more particularly to drives for dye jiggers and the like, some examples of prior art jiggers being disclosed in U. S. Patents Nos. 1,780,628; 1,958,676; 1,994,545 and 1,996,815.

One of the objects of my invention is to provide a drive for a dye jigger or the like and which is so constructed and arranged as to effect either tension or tensionless operation of the jigger, as desired.

An important object of my invention is to provide a drive of the foregoing described character which is capable of being applied to jiggers already in use without substantial modification thereof.

Another important object of my invention is to provide a drive for a dye jigger or the like which is simple in construction, durable in use, efficient in operation and economical in manufacture.

With the above and other objects in view, as will hereinafter appear, the invention consists in the combination and arrangement of parts hereinafter set forth and illustrated in the accompanying drawings from which the several features of the invention and the advantages attained thereby will be readily understood by those skilled in the art.

Referring to the drawings wherein like reference characters designate like parts throughout the several views:

Figure 1 is a top plan view of a dye jigger, partly broken away, equipped with my invention.

Figures 2 and 3 are sectional views taken on the lines 2—2 and 3—3, respectively, of Figure 1.

Figure 4 is a detail sectional view taken on the line 4—4 of Figure 1.

In practicing my invention, as illustrated in the drawings, I provide a dye jigger equipped with the usual tank 5 for containing a dyeing solution or bath and which is mounted within a base structure 6. The tank is provided with brackets 7 which support a bearing frame 8 above the tank. The frame has journaled therein coincident end sections of the shafts 9 and 10 of demountable rolls or beams 11 and 12, respectively, disposed over the tank and about which a web of cloth W or the like is wound. The tank 5 is provided with a plurality of guide rollers 13 for guiding the cloth, as it passes from one beam to another, through the bath as is the customary operation in dye jiggers.

The shafts 9 and 10 are provided with clutches 14 and 15, respectively, each having a clutch element 16 slidably keyed to the respective shaft

2

for operation into and out of operative engagement with a clutch element 17 rotatably mounted on the shaft and with the clutch element 17 being provided with a sprocket 18 over which is trained a sprocket chain 19 for a purpose hereinafter made apparent. The clutch elements are slidably operated on the shafts by the usual forks 20 which in turn are operated by arms 21, the latter being connected for unitary operation with a manually operated rod 22. The opposite end sections of the shafts 9 and 10 are each provided with the usual tension device 23 comprising a drum fixed to the shaft and about which drum is disposed an adjustable band carried by the frame whereby a desired tension or drag may be applied to the beams for effecting tension operation of the jigger.

The frame 8 has journaled therein, between the shafts 9 and 10, a power shaft 24 having fixed thereto a sprocket 25 which is connected by means of a chain 26 to a similar sprocket fixed to the drive shaft 27 of an electric motor 28, the latter being of the reversible type. The shaft 24 has mounted thereon a pair of spaced clutches 29 and 30, respectively. Each clutch comprises a clutch element 31 slidably keyed to the shaft 24 and a coacting element 32 rotatably mounted with respect to the shaft 24, the elements being provided with teeth for engagement with each other to effect unitary operation of the elements. The elements 32 are mounted upon and in fixed relation with the hubs 32a of a pair of spaced bevel gears 32b of a differential unit 33. The gears 32b are loosely mounted upon the shaft 24 and are disposed within the sectional housing 34 of the unit, the housing 34 being mounted for rotation upon the hubs 32a of the gears 32b. Disposed within the housing 34 are bevel gears 34a meshing with the gears 32a and each fixed 40 to a stub shaft 34b having its inner end journaled in a bearing 34c keyed to the shaft 24 for rotation therewith and its outer end journaled within the housing 34. Inasmuch as the differential unit 33 is of an ordinary construction and forms no part of the present invention per se, a more detailed disclosure thereof is not deemed necessary. The elements 32 of the clutches 29 and 30 have fixed thereto sprockets 35 about which is trained the chains 19, respectively. The elements 31 are operated into and out of engagement with the elements 32 by clutch forks 37 with the latter being actuated by arms 38.

In use, when it is desired to operate the apparatus as a tension jigger and to wind the cloth about the beam 12 from the beam 11, the ten-

sion device 23 on the shaft 10 is released to permit free rotation of the beam 12 while the tension device 23 of the shaft 9 is adjusted to effect rotation of the beam 11 under a desired tension or drag. When the devices 23 have thus been adjusted with the elements of the clutch 14 disengaged, the motor 28 is energized and effects clockwise rotation of the shafts 10 and 24 by reason of the respective elements of the clutches 15, 29 and 30 being engaged, the element 17 of the clutch 14 idling on the shaft 9. Rotation of the shaft 10 serves to wind the cloth about the beam 12 and to unwind the cloth from the beam 11. As the cloth passes from one beam to another, it is guided through the bath by reason of the guide rollers 13. By virtue of the drag applied to the beam 11 by the tension device, overrunning of the beam 11 is not only prevented but a desired tension applied to the cloth, it being understood that the unit 33 is driven with the shaft 24. By adjusting the devices in a reverse manner, disengaging clutch 15, engaging clutches 14, 29 and 30 and operating the motor in the opposite rotary direction, cloth may be transferred from the beam 12 to the beam 11.

In instances where it is desired to utilize the jigger in the dyeing of cloth by the tensionless method, the clutches 29 and 30 are disengaged while the clutches 14 and 15 are disposed in engagement and the motor is operated in a desired direction to effect travel of the cloth from one beam to another through the bath, it being understood that the tension devices are released to preclude drag on the beams and that the rod or bar 22 is disengaged from the arms 21 to permit simultaneous engagement of the clutches 14 and 15. When the drive is thus operated, the differential unit 33 functions to effect rotation of both beams at coordinated speeds to permit the build-up of the cloth on one beam without tension being exerted thereon by the other beam.

Without further elaboration, the foregoing will so fully explain the invention that others may, by applying current knowledge, readily adapt the same for use under various conditions of service. Moreover, it is not indispensable that all the features of the invention be used conjointly since they may be employed advantageously in various combinations and subcombinations.

It is obvious that the invention is not confined solely to the use herein disclosed in connection therewith as it may be utilized for any purpose to which it is adaptable. It is therefore to be understood that the invention is not limited to the specific construction as illustrated and described, as the same is only illustrative of the principles involved which are capable of extended application in various forms, and the invention comprehends all construction within the scope of the appended claims.

What I claim is:

1. In combination, a dye jigger equipped with selectively constituted supply and receiving beams rotatable for moving cloth through a dye bath beneath said beams for dyeing said cloth during travel of the latter from said supply beam to said receiving beam, tension means associated with said supply beam and capable of being rendered effective for exerting tension on said cloth during said travel for tension dyeing of said cloth and rendered ineffective with respect to said tension to permit tensionless dyeing of said cloth, power means, differential speed means, power transmitting means connecting said power means to said speed means and provided with

clutches connected to said beams and selectively operable for effecting coincident operation of said beams by said speed means at proportional speeds during build-up of the cloth on said receiving beam and unwinding of the cloth from said supply beam to insure tensionless dyeing of said cloth when said tension means is rendered ineffective and for effecting sole operation of said receiving beam by said speed means and idling of said supply beam relative to said power means to permit tension dyeing of said cloth when said tension means is rendered effective.

2. In combination, a dye jigger equipped with selectively constituted supply and receiving beams each having a driven shaft fixed thereto and rotatable for moving cloth through a dye bath beneath said beams for dyeing said cloth during travel of the latter from said supply beam to said receiving beam, a motor, tension means associated with said supply beam and capable of being rendered effective for exerting tension on said cloth during said travel for tension dyeing of said cloth and rendered ineffective with respect to said tension to permit tensionless dyeing of said cloth, a power shaft connected to and driven by said motor and equipped with a differential gear unit, power transmitting means connecting said driven shafts to said unit and provided with clutches carried by said unit and said driven shafts and selectively operable for effecting coincident operation of said driven shafts by said unit at proportional speeds during build up of the cloth on said receiving beam and unwinding of the cloth from said supply beam to insure tensionless dyeing of said cloth when said tension means is rendered ineffective and for effecting sole operation of said receiving beam by said unit and idling of said supply beam relative to said motor to permit tension dyeing of said cloth when said tension means is rendered effective.

3. In combination, an apparatus equipped with selectively constituted supply and receiving members rotatable for unwinding a web of material from said supply member and winding said web about said receiving member, respectively, to thus transfer said material from one member to another, tension means associated with one of said members and capable of being rendered effective for exerting tension on said web during said transfer and rendered ineffective with respect to said tension to permit tensionless transfer of said web, power means, differential speed means, power transmitting means connecting said power means to said speed means and provided with clutch means connected to said members and selectively operable for effecting coincident operation of said members by said speed means at proportional speeds during build-up of the web on said receiving member and unwinding of the web from said supply member to insure tensionless transfer of said web when said tension means is rendered ineffective and for effecting sole operation of said receiving member by said speed means and idling of said supply member relative to said power means to effect transfer of said web under tension when said tension means is rendered effective.

ANDREW JACK SEYERLEIN.
